CLAIM

The ornamental design for a compliance monitor for metered dose inhaler, as shown and described.

DESCRIPTION

FIG. 1 is a top plan view of a compliance monitor for metered dose inhaler according to a first embodiment; FIG. 2 is a left side elevation view of the invention of FIG. 1;

FIG. 3 is a front elevation view of the invention of FIG. 1; FIG. 4 is a right side elevation view of the invention of FIG. 1;

FIG. 5 is a rear elevation view of the invention of FIG. 1; FIG. 6 is a bottom plan view of the invention of FIG. 1; FIG. 7 is a perspective view of the invention of FIG. 1 shown attached to a metered dose inhaler;

FIG. 8 is a top plan view of a compliance monitor for metered dose inhaler according to a second embodiment; FIG. 9 is a left side elevation view of the invention of FIG. 8;

FIG. 10 is a front elevation view of the invention of FIG. 8; FIG. 11 is a right side elevation view of the invention of FIG. 8;

FIG. 12 is a rear elevation view of the invention of FIG. 8; FIG. 13 is a bottom plan view of the invention of FIG. 8; FIG. 14 is a perspective view of the invention of FIG. 8; and, FIG. 15 is a perspective view of the invention of FIG. 8 shown attached to a metered dose inhaler.

The broken lines shown in the figures depict portions of the compliance monitor for metered dose inhaler that form no part of the claimed design. The broken lines in FIGS. 1 and 8 define bounds of the claimed design and form no part thereof. The broken lines showing the metered dose inhaler are for illustration purposes only and form no part of the claimed design.
